CLAIM

(21) Appl. No.: **29/554,944**

The ornamental design for a capsule containing washing products, as shown and described.

(22) Filed: **Feb. 17, 2016**

DESCRIPTION

(30) **Foreign Application Priority Data**

FIG. 1 is a perspective view of a capsule containing washing products of the present invention;

Aug. 17, 2015 (EM) 002756205-0005

FIG. 2 is a side view of the capsule containing washing products of FIG. 1;

(51) **LOC (10) Cl.** **28-02**

FIG. 3 is the other side view of the capsule containing washing products of FIG. 1;

(52) **U.S. Cl.**

FIG. 4 is a back view of the capsule containing washing products of FIG. 1;

USPC **D28/8.1; D9/425**

FIG. 5 is a front view of the capsule containing washing products of FIG. 1;

(58) **Field of Classification Search**

FIG. 6 is a top view of the capsule containing washing products of FIG. 1; and,

USPC D9/424-426, 428, 430-432, 702, 707,

FIG. 7 is a bottom view of the capsule containing washing products of FIG. 1.

D9/710, 737, 759

The use of a separation and a bracket in each of FIGS. 1-7

CPC C11D 17/04; C11D 17/041-17/042; C11D

indicate that, for each illustration, the precise height of the capsule containing washing products is not known (i.e., the

17/043-17/047; C11D 17/0047-17/0091;

break lines in FIGS. 1-7 represent indeterminate length).

C11D 17/0095; C11D 17/00-17/0021

The capsule containing washing products is shown with a

See application file for complete search history.

symbolic break in its height. The appearance of any portion
